UNITED STATES PATENT OFFICE.

OTTO J. REICKERT, OF SPRINGFIELD, MASSACHUSETTS.

VEHICLE HEADLIGHT.

1,419,942.

Specification of Letters Patent. Patented June 20, 1922.

Application filed August 5, 1920. Serial No. 401,475.

To all whom it may concern:

Be it known that I, OTTO J. REICKERT, citizen of the United States, residing at Springfield, in the county of Hampden and 5 State of Massachusetts, have invented new and useful Improvements in Vehicle Headlights, of which the following is a specification.

This invention relates to an improved vehicle headlight which, while capable of being employed in various relations is particularly adapted for use in connection with automobiles and like vehicles for preventing glare generally objectionable in lights of 15 this character.

One object of the invention is to provide a device of this character wherein certain of the light-rays are deflected towards the axis of the light thus preventing these rays from 20 diverging to such an extent as to interfere with the driver of an approaching vehicle.

Another object of the invention is to provide a device of this character wherein the uppermost rays are bent downwardly thus 25 preventing glare and at the same time the light is rendered more efficient for lighting the ground over which the vehicle is travelling.

Another object of the invention is to provide a device of this character which is of 30 simple construction, efficient in operation, and which will not easily get out of order.

Other objects of the invention relate to details of construction and methods of operation as will more fully appear from the detailed description to follow.

Referring to the drawings:

Fig. 1 is a side elevational view, partially in section, showing the position of the segmental reflector relative to the other parts 40 of the headlight;

Fig. 2 is a front view of the headlight;

Fig. 3 is a perspective view of the segmental reflector;

Fig. 4 is a perspective view of a modified 45 form of segmental reflector; and

Fig. 5 is a detail sectional view showing a different manner of securing the segmental reflector in the headlight.

In the embodiment of the invention illustrated herewith the headlight comprises a casing 1 of substantially semi-spherical form which is adapted to be supported in any suitable manner. The casing may be of the usual or any desired construction, the form 55 shown herewith being merely for the purpose of illustration as any desired form may

be used with equal facility and any desired manner of constructing the same may be employed. A reflector 3 is positioned within the casing 1 being preferably so formed as 60 to make a parabolic curve with any plane passed through the axis A—B of the headlight. A socket 4 may be supported by the reflector at a point at or adjacent to the axis of the headlight and this socket is provided 65 with means whereby the wires 5 may be suitably connected to contact points for engagement by corresponding contacts in the base of the lamp 6.

The outer edge of the reflector 3 is turned 70 outwardly to form a flange 7 which may be supported in any suitable manner from the casing. A strip of suitable packing 8 extends about the flange 7 as is common in devices of this character for preventing 75 rattling of the parts and also to protect the glass 9 which bears thereagainst throughout a portion of its circumference. A cover member 10 provided with an inturned flange 11 formed at one end thereof, fits over the 80 open end of the casing to which it may be firmly secured by any suitable fastening devices (not shown). If desired, suitable packing may be interposed between the glass 9 and the flange 11 to protect the glass from 85 injury and prevent rattling of the parts.

The segmental reflector 12 has a curved inner surface portion 13 preferably so constructed as to form an efficient reflecting surface, and the segmental portion is made 90 of such size as to extend from a point in the rear of the lamp 6 to a point adjacent the glass. The rear narrowed portion of the segmental reflector has a slot 14 formed therein for receiving the socket 4 upon 95 which the rear portion of said reflector is supported. The forwardly extending widened portion of the segmental reflector is provided with an outturned flange 15 which is bent at such an angle to the main 100 body portion thereof as to contact with the glass 9 and be secured between the inner face of the glass plate and a portion of the packing 8. It is obvious that the forwardly extending portion of the segmental reflector 105 may be raised or lowered slightly as it is placed in position and may thus be secured in place at slightly different angles relative to the axis of the headlight depending upon the extent to which it is desired to deflect 110 the light rays.

In the modified form of the invention

2
shown in Fig. 4 of the drawings, the reflector is of similar construction to the reflector 12 previously described except that the flange 17 formed thereon extends throughout only a small part of the extent of the wider end of the reflector. The flange 17 is 5 preferably located substantially midway of the arc 18 and is preferably bent outwardly after the manner of the flange 15 previously 10 described whereby it may be readily secured between the inner face of the glass and the packing.

In the construction illustrated in Fig. 5 15 of the drawings, the flange 19 of the segmental reflector 20 is made somewhat longer than in the preceding forms and the end 21 of said flange is bent over the edge of the circular glass plate 22 whereby the segmental reflector is more firmly held in position and 20 retained against movement caused by the jolting of the vehicle. In each of the forms 25 of the invention shown, the segmental reflector makes a sharper angle with the axis of the headlight than the main reflecting surface thus causing those rays which strike 30 the reflecting segment to be bent more sharply and deflected inwardly toward the axis of the headlight so as to cross the same and when the reflecting segment is positioned at the upper portion of the headlight, the rays thus deflected will be directed towards the

roadway thus giving a greater intensity of light on the road and at the same time preventing the glare in the eyes of the driver of an approaching automobile caused by the 35 rays from the upper portion of the main reflector being directed forwardly in straight lines.

The invention has been disclosed herein in an embodiment at present preferred, for 40 illustrative purposes, but the scope of the invention is defined by the appended claim rather than by the foregoing description.

What I claim is—

The combination in a vehicle headlight 45 of a casing, a reflector, a lamp socket projecting therefrom, a lens, a deflector located within the upper part of the reflector comprising a curved sector of bendable reflecting material having an aperture near one 50 end thereof for embracing the lamp socket and a flange at its other end having a portion bent at right angles thereto that lies against the peripheral edge of the lens whereby the deflector is supported in a de- 55 sired spaced and angular relation with respect to the reflector thereby directing rays downwardly and obliquely with respect to the horizontal axis of the reflector.

In testimony whereof I have affixed my 60 signature.

OTTO J. REICKERT.
